TOURNIQUET

Albert Eschner, Santa Monica, Calif.

Application March 3, 1942, Serial No. 433,194

7 Claims. (Cl. 128—327)

This invention relates to an improved device for arresting bleeding.

Among the objects of the invention are:

To provide a tourniquet having an improved means for applying the desired pressure in a more definite and specific manner to the point on the flesh under which the artery or vein to be compressed is located; to provide an improved interlocking lever and fastening means for applying, regulating and maintaining the desired amount of pressure at the point required; and to provide an improved combination, with a lever having a foot portion to compress the injured blood vessel; of an elastic connection to encircle the bleeding limb, said connection having an end portion readily connectable with and disconnectable from said lever at a distance from its fulcrum, thereby to cause the aforesaid foot portion of said lever to press effectively upon the desired portion of tissue.

Another object is to provide a tourniquet which can be applied to an injured limb for the intended purpose in a quicker manner—an important feature in cases of severe hemorrhage.

The invention includes, as a new article of manufacture, a pair of attachments, one a hook member and the other an angular strip of rigid material, said pair of attachments being connectable with any suitable flexible connection to form, in conjunction therewith, a complete tourniquet.

The invention further includes the provision, in a tourniquet, of a novel lever for applying pressure to check hemorrhage, said lever being constructed in such a manner as to enable the manufacturer thereof to use inexpensive sheet metal in its production, or to use still less expensive wire, it being possible to do this without sacrificing the required strain-withstanding quality, and at the same time lightening the weight of the appliance.

Other objects, advantages and features of invention will hereinafter appear.

Referring to the accompanying drawing, which illustrates what is at present deemed to be preferred embodiments of the invention,

Fig. 1 is a plan view of the preferred embodiment of the invention in the extended position, a portion being broken away in order to contract the view.

Fig. 2 is a side elevation of the device illustrating the manner in which it is operatively applied.

Fig. 3 is a fragmentary side elevation of the applied device.

Fig. 4 is a perspective view of the pressing clamp per se.

Fig. 5 is a view similar to Fig. 1 showing an alternate embodiment of the invention.

Fig. 6 is a fragmentary view of the alternate species similar to Fig. 2, and

Fig. 7 is a view similar to Fig. 3 of the alternate species.

Referring in detail to the drawing, the flexible connection or band 10 for encircling one or more times the injured limb 11 is preferably of an elastic character. It has a folded over end portion 12 which is passed through the basal looped portion 13 of a wire hook 14, this folded over part being kept in its looped condition by an appropriate fastener, for example, the tubular rivet 15

15 passing therethrough.

The means shown in Figs. 1 to 4 whereby added pressure is applied directly over the injured vein or artery consists of an angular lever member 17 having an expanded middle portion 18 furnished 20 with a slot 19 through which the connection passes, and an expanded depressor foot 21, the end of the member 17 opposite to said foot having an operating arm 22 furnished at its outer end with an eye 23.

25 After the angular member 17 has been stamped out in a flat form with the hole 23 and a pair of slots through it, thereafter it is transversely bent between said slots and the metal adjacent to the bend is doubled over upon itself thereby bringing 30 said slots into register with each other to produce the slot 19 through which the connection 10 passes.

The presser foot 21 is of a generally circular shape and is joined to the slotted portion of the 35 angular member 17 by a narrowed neck portion 21a. Owing to the two sheet metal runs through which the slot 19 extends being in an abutting relation to each other the member 17 is strengthened at the point of greatest leverage. However, 40 these runs may be somewhat spaced apart except where they join the foot 21 and arm 22, where they should contact in order to impart added rigidity to this part of the structure. Said foot and arm are shown curved in the direction of 45 their length with their concave sides directed toward each other.

In Figs. 5, 6 and 7 a modification is shown wherein a wire member 31 is substituted for the member 17 of the other views. Said wire member 50 has its central, angular portion bent transversely to form a looped part 32 consisting of a plurality of runs of the wire with a slot 33 which extends transversely of the midlength portion of this angular wire member. At one side of its looped part 55 32 this member has an outbent wire arm 34 which

extends from the midlength portion of its loop 32 and forms a lever or operating arm which has an apertured extremity 35. Opposite to said arm 34, the member 31 has a wire run 36 which is outbent between its ends and which forms a depressor foot to bear down upon the vein or artery to be compressed when the member 31 is tilted as a whole by forcibly swinging its arm 34 in the proper direction, and is then maintained in the compressing position by engaging the hook 14 with the apertured extremity 35 of said arm.

In both forms of the invention the strap-like flexible connection 10 is shown of a sufficient length to pass twice or more times around the injured limb, and the apertured part (18 or 32) surrounds the outer run of the applied connection 10. In both cases an elastic connection 10 is preferably provided.

In operating both forms of the device, after the connection 10 has been wound around the injured limb till portions of said connection overlap as shown in Fig. 2, the foot portion (21 or 36) of the angular member being slidably connected with said connection, said angular member may be slipped along the outer run of the connection 10 until its said foot portion is positioned applying pressure to the limb at the proper point. Then the angular member (17 or 31), by means of its operating arm, will be swung to a position wherein its compressor foot (21 or 36) will bear down upon the part of the tissue to be pressed against to stop the hemorrhage, whereupon the hook 14 will be hooked into the apertured extremity of said operating arm to maintain the pressure desired. If, when the attempt is made thus to utilize the hooked arm 14 as a fastener, it be found that it is not in the proper position for such use, the operator can, after slipping his fingertips in between the overlapped connection 10 and the limb which it surrounds, impart a rotary adjustment to the device as a whole and thereby bring said hooked arm to the desired position; the angular compressor member can then readily be readjusted by sliding it along the outer run of the connection 10. However, no very accurate circumferential adjustment of the applied connection 10 in relation to the injured limb is necessary, because the elasticity of the connection enables the operator to stretch considerably the part of said connection adjacent to the hook 14 to utilize said hook in the manner aforesaid. The simple, elastic character of the device enables the user to apply it in a quick, accurate manner.

What is claimed is:

1. In a device of the kind described, a flexible connection for encircling the injured limb, an angular strip of rigid material bent in a flatwise manner at a point considerably spaced away from both of its ends, said strip being adjacent to its bend swingably connected with said flexible connection, one end portion of said angular strip constituting a foot portion to apply pressure over the injured vein or artery and the opposite or outer end thereof being shaped to receive a fastening element, and a fastening link one end of

which is secured to the aforesaid flexible connection and the opposite end of which is engageable with the aforesaid outer end portion of said angular member to maintain said member in an inswung position wherein its foot portion exerts compression upon the artery or vein.

2. The subject matter of claim 1 and, said angular strip having a slot at its bend through which said flexible connection passes, said connection being gripped by the slotted part of said strip when the latter is in the inswung position.

3. The subject matter of claim 1 and, said angular member consisting of a wire having its angular portion furnished with a transverse loop through which said flexible connection passes.

4. In a device of the kind described, a rigid strip of metal transversely bent at a considerable distance from both ends and having a compressible foot at one end, there being adjacent to each side of the bend a slot through the strip, the bent portion of the strip being doubled over upon itself thereby bringing the two slots substantially into register with each other to form a single opening through the strip as a whole, a flexible strap passing through the opening formed as aforesaid, said strap being of a sufficient length to surround at least once the limb to which the device is to be applied, and means to connect with said strap the end of said rigid strip opposite to its said foot portion to maintain said foot portion in a down pressing relation to the injured vein or artery.

5. In a device of the kind described, a flexible strap-like connection, a single piece of wire having a transversely looped portion which is in a spaced relation to its ends and through the loop of which said strap-like connection extends, said looped part of the wire having at one side an outwardly directed operating arm and at the side thereof opposite to said operating arm an outbent run forming a part of a second loop, said outbent run serving as a depressor foot to apply pressure to the injured vein or artery when the wire as a whole is tilted by means of its said operating arm, and a linkage means fastened to said connection and connectable with the outer part of said operating arm to maintain said depressor foot in its depressing position.

6. A tourniquet consisting of a flexible connection for passing around a bleeding limb, a strip of rigid sheet material which in a spaced relation to its ends is bent flatwise down upon itself and which is furnished with an aperture through both plies of a bent down part through which said connection passes, said strip having at one side of its bent down part an operating arm and at the opposite side of said part a presser foot, and means carried by said connection to detachably connect with said arm to maintain said strip in its operative compressing position.

7. The subject matter of claim 6 and, said presser foot being a generally circular plate with a narrowed neck portion whereby it is united to the slotted portion of the strip of which it forms a part.

ALBERT ESCHNER.
